(57) **CLAIM**

The ornamental design for a hair styling apparatus, as shown and described.

DESCRIPTION

FIG. 1 is a front, top, and left side perspective view of the hair styling apparatus shown removed from environment;
FIG. 2 is a bottom plan view thereof;
FIG. 3 is a front elevation view thereof;
FIG. 4 is a rear elevation view thereof;
FIG. 5 is a left side elevation view thereof;
FIG. 6 is a bottom and left side perspective view thereof;
FIG. 7 is a top plan view thereof;
FIG. 8 is a rear, top, and left side perspective view thereof;
FIG. 9 is a front, top, and left side perspective view of the hair styling apparatus shown in an environment of use;
FIG. 10 is a bottom plan view thereof;
FIG. 11 is a front elevation view thereof;
FIG. 12 is a rear elevation view thereof;
FIG. 13 is a left side elevation view thereof;
FIG. 14 is a bottom and left side perspective view thereof;
FIG. 15 is a top plan view thereof; and,
FIG. 16 is a rear, top, and left side perspective view thereof. The broken lines in the drawings depict portions of the hair styling apparatus that form no part of the claimed design.
